UNITED STATES PATENT OFFICE.

GUSTAV SCHWAB, OF CHICAGO, ILLINOIS, ASSIGNOR TO AUGUST PUTSCH, OF SOUTH BETHLEHEM, PENNSYLVANIA.

COKE-OVEN.

989,302.

Specification of Letters Patent. Patented Apr. 11, 1911.

Application filed April 21, 1910. Serial No. 556,840.

To all whom it may concern:

Be it known that I, GUSTAV SCHWAB, a subject of the Emperor of Germany, residing at Chicago, in the county of Cook and State of Illinois, have invented a new and useful Improvement in Coke-Ovens, of which the following is a specification.

My invention relates particularly to ovens adapted to produce coke from coal; and my 10 primary object is to provide an improved oven-structure involving the use of improved heating-flue construction between the series of ovens employed in the structure, whereby the heat employed for coking 15 purposes may be more effectively and more completely utilized, whereby the oven-structure will be less liable to injurious effects from contraction and expansion, the life of the structure will be lengthened, and, in general, coke may be produced more economically than in ovens of known construction.

The invention also renders it possible to construct the ovens of any desired size without necessitating special reinforcement, and 25 without loss of economy in operation.

The invention involves, in the form illustrated, a construction wherein are employed a series of ovens whose lateral walls are formed by specially constructed vertically 30 disposed heating flues so designed as to communicate heat to the ovens in the most efficient manner and to withstand effectively the contraction and expansion incident to the reversal of the course of the products 35 of combustion usual in an oven of the regenerative type.

The invention is illustrated in the preferred embodiment in the accompanying drawings in which—

40 Figure 1 represents a broken sectional view of an oven constructed in accordance with my invention, the section being taken parallel with one side or front of the oven, as indicated at line 1 of Fig. 2; Fig. 2, a 45 transverse section taken as indicated at line 2 of Fig. 1, the section cutting one of the oven chambers; Fig. 3, a broken longitudinal section taken approximately as indicated at line 3 of Figs. 2 and 4, the section 50 at the upper portion of the figure being taken on a stepped line, as indicated by the broken walls, the purpose being to show the inspection openings through the upper walls of the structure as well as the charging 55 openings therethrough; Fig. 3^a, a broken section on an enlarged scale, showing the flue construction, the section being taken as indicated on line 3^a of Fig. 6; Fig. 4, a transverse section taken as indicated at line 4 of Fig. 3, this section passing through a vertical flue series separating two ovens; Fig. 5, a broken horizontal section, taken, as indicated, on line 5 of Fig. 4; Fig. 6, a broken plan view showing a fragment of the flue construction.

In the construction illustrated, the oven-structure comprises a base wall 1 and lateral walls 2 and 2^a; a series of ovens 3 having openings 4 through said lateral walls; a vertical flue series 5 between each two adjacent ovens and forming the lateral walls of said ovens; longitudinal gas mains 7 at each side or front of the coke-oven structure, from each of which rises a series of gas pipes 8, and a series of gas pipes 8^a adapted to be alternately used, said gas pipes being controlled, respectively, by gas cocks 9 and 9^a; a laterally disposed chamber 10 for each gas main and the gas pipes rising therefrom; a pair of longitudinally extending main conduits 11 and 11^a which extend through the base of the structure and are located near the sides of the structure, and which serve alternately as air admission and combustion products outlet conduits; a series of transversely extending regenerator conduits 12 located in the base 1 of the structure beneath alternate ones of the ovens 3, and communicating with the main conduit 11; a series of similar regenerator conduits or chambers 12^a located beneath the remaining alternate ovens and communicating with the main conduit 11^a; a series of conduits 13 connecting the conduits 12 with the main or longitudinal conduit 11; a series of conduits 13^a connecting the conduits 12^a with the longitudinal conduit 11^a; valves 13^b controlling the conduits 13, and valves 13^c controlling the conduits 13^a; a series of comparatively small conduits 14 disposed just beneath the bottoms of the ovens and above the conduits or regenerative chambers 12; a series of alternating conduits 14^a disposed above the regenerative conduits 12^a and beneath the bottoms of the corresponding ovens; passages 15 through which the conduits 12 are in communication with the conduits 14; passages 15^a through which the conduits 12^a are in communication with the conduits 14^a; two series of in-

clined passages 16 through which the conduits 14 communicate with alternate vertical flues of the two flanking heating flue series, and two series of inclined passages 5 16^a through which the conduits 14^a communicate with alternating vertical heating flues of the two flanking heating flue series.

Generally speaking, the walls of the coke-oven structure are composed of brick, but 10 any suitable material may be employed. As shown, the base wall 1 has, in its lateral surfaces, openings 17, through which, in Fig. 1, may be viewed the walls of the conduit 11, and the view-openings 6 leading to conduits 15 12 and 12^a. In practice, the openings 4, at the ends of the ovens, are closed by doors (not shown). Through the upper wall of 20 the structure extend charging openings 18 leading to the ovens and vent openings 19 25 communicating with the ovens; also view openings 20 enabling the vertical flues to be inspected.

Each flue series 5 is preferably constructed in the manner shown in detail in Figs. 3^a, 5, 25 6. As thus constructed, each flue series is provided with a vertical series of flues 21 which, in pairs, alternate with the pairs of a vertical series of flues 22. The flue construction is such that each flue has triangular vertical walls, and the preferred manner of securing such triangular walls is to construct two substantially parallel walls 23 which are joined by oblique walls 24. The oblique walls 24 and the parallel walls 23, in 35 part, are formed by means of Y-shaped bricks having a stem or base 25 and arms 26. In laying the walls, the stems or base portions 25 alternate with simple or straight bricks 27 at one wall 23, while the extremities of the arms abut against simple or 40 straight bricks 27 in the opposing wall 23. In the next course, the stems or base portions 25 are laid as a part of the other wall 23, being placed so that the base portions of the 45 arms projecting from each stem will lie over the free end portions of the arms of the underlying course of Y-shaped bricks. As thus constructed, the Y-shaped bricks are firmly bound together and also bound to the parallel walls, it being understood that the Y-shaped bricks of one course bear what may 50 be termed a staggered relation to the Y-shaped bricks of the next course. The flues 21 communicate through the passages 16 with the conduits 14, and the flues 22 communicate through the passages 16 with the conduits 14.

Each vertical gas pipe 8 is provided with a pair of inturned branches 29 and 30 which 60 communicate with channels or gas passages 31 and 32 respectively. The channels 31 are disposed directly beneath the heating flues and extend inwardly from the lateral surfaces of the structure approximately one-quarter of the distance across; and the pas-

sages 32 communicate with channels 33 which are separated from each other by a wall 34 and from the channels 31 by walls 35. The channels 31 and 33 communicate with the vertical heating flues 21 through inclined passages 36. The gas pipes 8 communicate through branches 29^a and 30^a with passages 31^a and 32^a similar to the passages 31 and 32 and lying close beside them, the passages 32^a communicating with passages 33^a which lie side by side with the passages 33 and are similar thereto. The passages 31^a and 33^a communicate through inclined passages 36^a with the vertical flues 22.

The operation will be readily understood from the foregoing detailed description. We may assume the conduit 11^a to be placed in communication with the smoke stack or chimney and the conduit 11 to be placed in communication with the atmosphere by the usual means (not shown). As thus arranged, assuming the valves 9 controlling the vertical gas pipes 8 to be opened, as by means of a chain 37, gas will be supplied to the channels 31 and 33, whence it will pass through the passages 36 to the vertical heating flues 21. At the same time air will be drawn through the longitudinal conduit 11 and cross conduits 12, whence it will pass through the passages 15 to the smaller cross conduits 14^a and thence through the inclined passages 16 to the vertical flues 21, where it will unite with the gas to form the products of combustion, the burning gases then passing through the spaces 38 at the upper ends of the walls separating the flues 21 from the flues 22, as indicated in Fig. 4, thence down through the flues 22, the passages 16^a, the small cross conduits 14^a, and the passages 15^a to the larger cross conduits or regenerators 12^a, and thence to the longitudinal conduit 11^a which is in communication with the chimney. After operation in this manner for a predetermined period, the operation is reversed, the longitudinal conduit 11 is placed in communication with the chimney and the conduit 11^a is placed in communication with the atmosphere. The gas cocks 9 are then closed and the gas cocks 9^a opened, whereupon the combustion begins in the vertical flues 22 and is continued by a down draft through the flues 21, the outlet being through the inclined passages 16, the small cross conduits 14, the passages 15, the large cross conduits or regenerators 12 and finally through the longitudinal conduit 11 to the chimney.

It will be noted that by reason of my improved flue construction the heat is evenly distributed to the ovens flanking the flue series, the flues are so arranged as to enable expansion and contraction to occur without injurious results, the walls being mutually bracing, and the most efficient use is made of the heat units generated by the burning gases.

While the invention is illustrated in connection with a coke-oven employing vertical heating flues and horizontal ovens, it will, of course, be understood that the invention 5 is not limited to this type of oven.

As will be understood from Figs. 1 and 3, the ovens are larger at their bases than at their upper portions, and this result is obtained by gradually enlarging the flues, 10 or, if desired, the flue walls, from the lower portions of the flues to their upper portions. I have shown the lateral walls 2 and 2^a of the oven-structure provided with view openings 39 which are in alinement with view 15 openings 39^a in the alternating wall extensions 40 at the upper ends of the flues. View openings 41 extend through the upper walls 42 which cap the flue series, the view openings 41 communicating with the enlarged 20 openings or chambers 20 shown in Fig. 3 and which have heretofore been mentioned. The chambers 20 are covered by removable plates 43 giving access to the longitudinal 25 chambers 20. The view openings 39 are ordinarily closed and the openings 39^a are 30 too small to interfere with the draft of the heating flues, but are large enough to enable the operation to be viewed. The view-openings 41 are covered by removable bricks 43.

The foregoing detailed description has 35 been given for clearness of understanding only, and no undue limitation should be understood therefrom, but the appended claims should be construed as broadly as permissible in view of the prior art.

What I regard as new and desire to secure by Letters Patent is:—

1. In a coke-oven structure, the combination of ovens and interposed heating flue 40 series, each heating flue series comprising lateral walls and oblique walls joining the same to form flues of triangular cross section for the purpose of strengthening said flue walls.

2. In a coke-oven structure, the combination of a series of ovens and interposed heating flue series, each heating flue series having flues of substantially triangular cross section lying adjacent each other.

3. In a structure of the character set forth, the combination of a series of ovens and interposed heating flue series having substantially triangular flue passages communicating in pairs at the end remote from the 55 point of introduction of heat.

4. In a structure of the character set forth, the combination of a series of ovens and interposed heating flue series, each series composed of lateral walls, and oblique walls 60 joining the flue passages of said series communicating in pairs at the end remote from the point of introduction of the burning gases.

5. In a structure of the character set forth, 65 the combination of a series of ovens and in-

terposed heating flue series, each series comprising lateral walls and oblique walls joining said lateral walls, said walls being formed in part of Y-shaped bricks.

6. In a structure of the character set forth, 70 the combination of a series of ovens and interposed heating flue series, each heating flue series comprising lateral walls and oblique walls joining said lateral walls, said lateral walls formed, in part, of simple bricks and 75 said oblique walls formed by the branches of Y-shaped bricks whose stems form a part of said lateral walls.

7. In a structure of the character set forth, 80 the combination of a series of ovens and interposed heating flue series, each series comprising lateral walls and oblique walls joining said lateral walls, said lateral walls being formed in part of simple bricks and 85 said oblique walls formed by the branches of Y-shaped bricks whose stems form a part of said lateral walls, the Y-shaped bricks of one course being staggered and reversed with relation to the Y-shaped bricks of the next 90 course.

8. In a structure of the character set forth, 95 the combination of a series of ovens and interposed heating flue series, having flues of substantially triangular cross section lying adjacent to each other, each heating flue series having a direct flue and a return flue in communication with each other at the far end, the flue series having series of pairs thus arranged, and said pairs of flues being separated from each other by walls at their far 100 ends.

9. In a structure of the character set forth, 105 the combination of a series of ovens and interposed heating flue series, each heating flue series composed of a pair of substantially parallel walls and oblique walls joining said parallel walls and forming substantially triangular flue passages, alternate oblique walls being recessed at the far ends of the flues, whereby direct and return flues lying adjacent to each other are provided.

10. In a structure of the character set forth, 115 the combination of a series of ovens, a pair of main conduits adapted to be placed in alternate communication with the chimney and atmosphere, a series of cross conduits connected with each main conduit, heating flue series having flues of substantially triangular cross section and forming walls for the ovens and composed of direct 120 and return flues arranged in pairs lying side by side, passages connecting the direct flues with one series of cross conduits, passages connecting the return flues with the other series of cross conduits, and means for supplying heat to either series of heating flues, at will.

11. In a structure of the character set forth, 125 the combination of a series of ovens, a pair of main conduits adapted to be alter-

nately placed in communication with the atmosphere and with the chimney of the structure, a series of cross conduits connected with one of said main conduits and disposed beneath alternate ovens, a series of cross conduits alternating with the first named series of cross conduits and connected with the other main conduit, heating flue series separating said ovens and consisting of a series of direct and return heating flues substantially triangular in cross section, passages

connecting one series of cross conduits with the direct flues, passages connecting the other series of cross conduits with the return flues, and means for introducing fuel gas into 15 either the direct flues or the return flues, at will.

GUSTAV SCHWAB.
